[57] CLAIM

The ornamental design for a modular grid surfacing unit, as shown and described.

DESCRIPTION

FIG. 1 is a top plan view of a modular grid surfacing unit showing our new design;

FIG. 2 is an elevational view taken along line 2—2 in FIG. 1;

FIG. 3 is an elevational view taken along line 3—3 in FIG. 1;

FIG. 4 is an enlarged fragmentary top perspective view; and

FIG. 5 is a bottom plan view.
